UNITED STATES PATENT OFFICE.

HARRY C. HORNISH, OF INDIANAPOLIS, INDIANA.

VAPOR-BURNER.

SPECIFICATION forming part of Letters Patent No. 601,752, dated April 5, 1898.

Application filed February 15, 1897. Serial No. 623,537. (No model.)

To all whom it may concern:

Be it known that I, HARRY C. HORNISH, a citizen of the United States, residing at Indianapolis, in the county of Marion and State 5 of Indiana, have invented certain new and useful Improvements in Vapor-Burners; and I do hereby declare the following to be a full, clear, and exact description of the invention, such as will enable others skilled in the 10 art to which it appertains to make and use the same.

My invention relates to improvements in vapor-burners; and the objects in view are to simplify and cheapen the construction of 15 the burner as a whole, to adapt it to be readily dismembered for cleaning or for a renewal of any of its impaired parts, and to provide a new and improved combined vapor cut-off and guide, by the use of which cut-off a subflame 20 may be maintained.

Other objects and advantages of the invention will hereinafter appear, and the novel features thereof will be particularly pointed out in the claims.

25 Referring to the drawings, Figure 1 is a side elevation of my improved vapor-burner. Fig. 2 is a top plan view of the same with the burner-cap removed. Fig. 3 is a bottom plan view of the retort. Fig. 4 is a transverse sectional view of the retort in detail, the construction of retort being slightly modified, as will hereinafter appear.

Like numerals of reference indicate similar parts in all the figures of the drawings.

35 The retort consists of the annular hollow chamber 1, which incloses a solid bottom 2, at the center of which is formed an opening 3. This bottom 2 may be cast integral, and preferably is so cast, with the hollow annular 40 chamber 1 and may be located at the bottom edge of said chamber, as in Figs. 1, 2, and 3, or located at any suitable point between the bottom and top edges thereof, as indicated at 4, Fig. 4.

45 The bottom plate 2 may have its opening provided with an annular mixing-tube 5, cast thereon, the same rising to a point about on a level with the upper side of the chamber 1 of the retort, or, as preferred, such tube 5 may 50 be cast on a separate and removable disk or plate 6, adapted to rest upon the bottom plate 2, in which instance, as best shown in Fig. 4,

the lower end of said tube projects below the said disk, taking within and fitting the opening 3, with which it (the bottom) is provided. 55 It is therefore perfectly obvious that the disk and the mixing-tube may at any time be removed for cleaning or for the substitution of a smaller mixing-tube or a new one to take the place of one burned out. By extending 60 the lower end of mixing-tube through the central opening in the bottom plate soot cannot accumulate between the two plates and disturb the snug fitting of these parts.

An annular rib 7 surrounds the upper outer 65 edge of the annular chamber 1 of the retort, serving to strengthen the same at this point, and having its inner surface inclined or flared, as shown, will serve to properly direct the flame, as will hereinafter appear. At intervals lugs 8 are formed on the upper surface of the chamber 1 and extend radially from the flange 7, the same serving to readily center the burner-cap 9 and retain the same in proper relative position with the rib 7. 70

75 For the purpose of facilitating cleaning of the annular chamber 1 I also provide the same with openings 10, closing the same securely with threaded plugs 11, which may be readily removed by the application of a wrench. 80

A hollow leg 12 depends from the under side of the annular chamber 1 and is provided at its lower end with a threaded opening 13 for the reception of a closing-plug 14, which, passing through a suitable hole formed 85 in the tray 15, serves to not only close the lower end of the said leg, but also to clamp and hold in position the aforesaid tray 15 under and in proper relation to the retort. Above the tray the leg is provided with dia- 90 metrically opposite openings 16 and 17, the former being occupied by the supply-pipe 18 and the latter by a removable threaded plug 19, whereby access to the said leg for cleaning purposes is given. 95

A flanged opening 20 is located in the bottom of the annular chamber 1 diametrically opposite to the point of location of the leg 12, and in the same is threaded a bushing 21, which receives the upper end of the usual 100 needle-valved vapor-discharge 22, the same being of ordinary construction and therefore not requiring any particular mention.

Pivoted eccentrically to the bottom plate

2 of the retort, as indicated at 23, is a substantially triangular plate 24, the same forming a cut-off. Cast or otherwise secured to the under side of the said cut-off plate is a 5 pair of segmentally-shaped open and closed tubes 25 and 26, respectively, the same being located at an acute angle to each other and connected by an intermediate web 27.

The cut-off plate 24 is provided with an 10 opening 29, (see dotted lines, Fig. 3,) which when the plate is moved so that the tube 25 is in line with the mixing-tube forms a continuation of the said mixing-tube and the tube 25. That part of the plate 24 which is 15 above or in line with the tube 26 is imperforate or solid, so that when the latter tube 26 is in line with the mixing-tube communication between the two tubes is interrupted or cut off. The tube 26, however, immediately 20 below the cut-off plate is provided with a horizontal escape-slot 30, through which oil and vapor may escape into the pan or tray for the purpose of a preliminary starting and to maintain a subflame underneath the retort 25 after the operation has commenced and when it may be desired to maintain vaporization within the retort until such time as it may be desired to use the burner at its full capacity. A curved keeper-bar 31 is located under the 30 retort and loosely confines the arm 28, which projects from the cut-off plate 24 between the two tubes 25 and 26. This bar has at its ends upwardly-projecting posts 32, which at their upper ends abut against the bottom of the 35 retort and are bored for the passage of screws 33, which are passed therethrough and into the bottom of the retort for the purpose of securing the keeper-bar in position. At the same time that the bar aids in confining the 40 arm 28 the upwardly-projecting posts serve as stops for the arm to abut against and thus limit the throw or movement of the cut-off as a whole. It will thus be seen that when the cut-off is thrown to the limit of its movement 45 in one direction the tube 25 will be in line with the opening or vapor-tube, and when moved to the limit of its passage in the opposite direction the opposite tube 26 will be in line with the vapor tube or opening, and the 50 cut-off plate will be interposed between the two. By thus forming the cut-off it will be seen that the gas and air will be mixed therein and a subflame be ejected or discharged from the slot at the upper end thereof below 55 the cut-off plate. This subflame, it will be understood, will be sufficient to maintain the state of vaporization of the oil in the retort, so that the burner can be instantly started by swinging the cut-off plate to the opposite side, 60 so as to bring the vapor-tube in line with the mixing-tube and vapor-discharge.

The interior of the burner-cap 9 may be flat, or, as shown by dotted lines, Fig. 1, it 65 may be concaved, and in either instance is surrounded by a vertical flange 34, which projects at its upper end above the exterior or dome of the cap to form a surrounding

strengthening-flange or thickened portion 35. This wall or flange 34 is preferably provided at intervals with perforations 36, the same 70 being arranged in annular alinement and in a lower plane and also in annular alinement and preferably alternating with the perforations 36. Said flange is further provided with openings 37 of substantially keyhole 75 shape, inasmuch as they consist of upper circular openings communicating by means of narrow slits with the bottom edge of the cap or, rather, flange. These openings, it will be understood, constitute the means of escape of 80 the flame, and after they thus escape they are directed upwardly by the flared flange 7.

The operation of this burner does not materially differ from that of others, and may be briefly said to consist in permitting a suitable quantity of oil to pass through the feed-pipe 18 into the retort-chamber 1, after which the supply is cut off. A small quantity of oil being permitted to escape into the tray is now ignited and warming the retort vaporizes the 90 oil in the retort, the needle-valve being operated to permit the escape of the vapor into the tube 25, from which it passes into the tube 5, at the upper end of which it is ignited. During its passage through these tubes it 95 of course mixes with the air, as is usual in this class of inventions. When it is desired to shut off the burner temporarily and to maintain such a subflame as will maintain a vaporization, the cut-off plate is moved so 100 as to bring the tube 26 between the vapor-opening in the needle-valve and the mixing-chamber, whereby the vapor escapes through the slot 30 in the tube 26 and heats the retort to such an extent as to bring about the 105 desired result.

I do not limit my invention to the precise details of construction herein shown and described, but hold that I may vary the same within the knowledge of the skilled mechanic 110 without departing from the spirit of my invention or sacrificing any of its advantages.

If desired, the mixing-tube 5 may be tapered or decreased in diameter toward its upper end, such being indicated in Fig. 4 by 115 means of dotted lines. It will also be understood that any desired shape of opening may be formed in the burner-cap.

Having described my invention, what I claim, and desire to secure by Letters Patent, 120 is—

1. A retort comprising a hollow annular chamber, a web or bottom plate surrounded and supported thereby, said plate being provided with a central opening, and a removable disk seated on said plate and surrounded by the chamber and provided at its center with an annular flanged opening corresponding with the opening in the bottom plate, substantially as specified. 125

2. A retort, comprising a hollow annular chamber, a bottom plate supported by and surrounded by the said chamber, and provided with a central opening, and a removable disk 130

seated on and supported by the bottom plate, and provided at its center with an opening registering with that of the plate, said opening in the disk being provided with a surrounding collar or flange, the lower end of which projects below the disk and fits removably in the opening in the bottom plate, substantially as specified.

3. The combination with a retort provided with a mixing-chamber and a vapor-discharge located below the latter, of a pair of movable tubes either of which is adapted to be moved into line with the vapor-discharge and mixing-chamber to the exclusion of the other, and one of which is provided with a lateral discharge out of line with the mixing-chamber and closed at said upper end.

4. The combination with a retort having a mixing-chamber, and a vapor-discharge located below the same, of a cut-off plate eccentrically pivoted with relation to the said mixing-chamber and provided with an opening that may be caused to register with the chamber by a movement of the plate, a tube 25 extending from the opening in the plate and so disposed that when in line with the mixing-chamber to align with the vapor-discharge, and a second tube similarly located with relation to the mixing-chamber and vapor-discharge and extending from an imperforate 30 part of the plate and provided below the same with a lateral discharge.

5. The combination with a retort having a mixing-chamber, a vapor-discharge located below the same, of a cut-off plate eccentrically pivoted to the under side of the retort at one side of the mixing-chamber and provided with an opening that may be caused to register with the chamber by a movement of 35 the plate, a tube extending from the opening in the plate and so disposed that when in line with the mixing-chamber it will also be in alinement with the vapor-discharge, a second tube similarly disposed and located with 40 relation to the mixing-chamber and vapor-discharge and extending from an imperforate part of the plate and provided with a lateral discharge, and means for limiting the pivotal movements of said plate whereby one or the 45 other of said tubes will be brought into alinement as mentioned when the movement of the plate has been arrested by one of said stops.

6. The combination with a retort having a mixing-chamber, and a vapor-discharge located adjacent thereto but spaced therefrom, of a movable vapor-guide located between the said vapor-discharge and the mixing-chamber, and a tube eccentrically and pivotally supported with relation to the mixing-chamber and vapor-discharge, said tube being adapted to be moved into alinement with the vapor-discharge and the mixing-chamber and having its upper end closed and provided below the same with a side discharge-opening. 55 60 65

7. The combination with the annular retort provided with the centrally-located mixing-chamber, of the vapor-discharge located below and at one side of said mixing-chamber, a cut-off plate pivoted to the under side 70 of the said retort eccentrically with relation to the mixing-chamber, said cut-off plate having an opening adapted to be registered with the mixing-chamber, a curved tube projecting downwardly and laterally from the opening in the cut-off plate so as to form a continuation of the mixing-chamber, and a companion similar tube extending from an imperforate part of said plate and provided with a side discharge below the said plate. 75 80

8. The combination with the retort having the centrally-located mixing-chamber, and the valved vapor-discharge at one side of and below the chamber, of a plate pivoted to the under side of the retort and the said chamber and provided with an opening in line with the chamber, an arm extending from the plate, a curved keeper-bar located under the arm and terminating in posts secured to the under side of the retort and forming stops for limiting the movement of the arm and plate, and a pair of tubes secured to the plate and curved so as to form a continuation of the mixing-chamber when in line with the vapor-discharge, one of said tubes being located in line 85 90 95 with the opening in the plate and the other of said tubes having its upper end closed by said plate, and provided at one side below the plate with a slit or escape-opening for the vapor, substantially as specified. 100

In testimony whereof I affix my signature in presence of two witnesses.

HARRY C. HORNISH.
